UNITED STATES PATENT OFFICE.

CARL B. SANDERS, OF MUSKOGEE, OKLAHOMA.

FOOT-COOLER FOR AUTOMOBILES.

1,316,111.

Specification of Letters Patent. Patented Sept. 16, 1919.

Application filed March 12, 1918. Serial No. 282,070.

To all whom it may concern:

Be it known that I, CARL B. SANDERS, a citizen of the United States, residing at Muskogee, in the county of Muskogee and State 5 of Oklahoma, have invented certain new and useful Improvements in Foot-Coolers for Automobiles, of which the following is a specification.

This invention relates in general to automobiles and has particular reference to a device which will direct air currents into the body of the vehicle causing the cool air currents to cool the feet of the chauffeur.

Another object of this invention is the 15 production of a foot cooler for automobiles which consists in a hinged shutter, whereby the shutter may be moved to an open position to direct air currents into the interior of the vehicle body, although when desired 20 the shutter may be moved to a closed position to prevent rain or very cold winds from being deflected thereby into the interior of the vehicle.

A still further object of this invention is 25 the production of a foot cooler for automobiles which includes in combination with the hinged shutter, a simple and efficient latching means for positively holding the shutter in an opened or in a closed position 30 at the desire of the operator.

One practical form of construction and assembly of the present invention will be hereinafter described and is illustrated in the drawing, in which—

35 Figure 1 is a fragmentary side elevation of an automobile body, showing the present invention in elevation.

Fig. 2 is an enlarged elevation of the device, the shutter being in an open position.

40 Fig. 3 is a central horizontal section through the construction, the latching means being shown in top plan.

Fig. 4 is a vertical section through the device, the latching means being shown in side 45 elevation.

Fig. 5 is an enlarged fragmentary elevation of a portion of the device, one of the links of the latching mechanism being removed.

50 In the preferred embodiment of the present invention about to be described, 10 indicates in general the foot cooler which is carried by the body 11 of the motor vehicle, at a point where the air currents deflected by 55 the shutter, to be hereinafter described will be deflected into the interior of the body 11

adjacent the feet of a person, thus causing the inner lower portions of the vehicle body to be efficiently cooled.

The foot cooler 10 comprises a frame 60 formed of a pair of rectangular plates 12 having the rectangular openings 13 formed centrally therethrough. Each plate 12 has flanges 14 formed thereon around its respective opening 13, it being noted, by referring to Fig. 4 that the flanges of one plate extends in the opposite direction to the flanges of the other plate. Accordingly, the flanges of one plate may be telescoped upon the flanges of the remaining plate, thus 35 bringing the plates 12 into engagement with the surfaces of the body 11 of the vehicle. At this time, suitable retaining bolts 15 may be passed through the plates and nuts 16 are screwed onto the projecting ends of the 70 bolts, thus fixing the plates in set position, whereby the frame of the cooler will be held in an operative position upon the body of the 75 motor vehicle.

The shutter 17, which is substantially the 80 same size as the opening through the frame, being slightly larger than the opening to efficiently cover the same when desired is provided. This shutter 17 has sleeves 18 thereon which fit upon sleeves 19 carried by 85 the frame of the device, a pivot pin 20 extending through the sleeves 18 and 19 and thus pivotally or hingedly mounting the shutter 17 upon the frame. Therefore it is obvious that when desired the shutter may 90 be swung to a closed position as shown in Fig. 1 to prevent the passage of air currents through the frame into the body of the vehicle, or the shutter may be opened as indicated in Fig. 2 to allow air currents to be deflected thereby into the body of the vehicle. A retaining staple 22 is fixed upon the inner 95 surface of the shutter 17 and it carries a clip 23. One end of the operating lever 21 is pivotally connected to the clip 23 and has a notch 25 adjacent its end which is connected to the clip and with a notch 26 adjacent its free end.

A bracket 27 is fixed upon the frame within the opening thereof as shown in Figs. 4 and 5. The bearing block 28 has a base 29 resting upon the horizontal portions 27' of the bracket 27 and a stem 30 extends from the base 29 of the bearing block 28 to extend through the bracket and be retained 110 by the pin 31. Therefore, the bearing block 28 will be free to rotate upon the bracket 27,

A pair of links 32 are provided and these links are positioned upon opposite sides of the lever 21. Each link has one end thereof connected to the lever 21 by a pivot pin 33 at a point adjacent the center of the lever, while the remaining ends of the links are pivotally mounted upon the pin 34 carried by the block 28.

When the shutter 17 is in an open position as shown in Figs. 2 and 4 inclusive, the lever 21 will be engaging the lock 28, the block being received within the notch 26 at the free end of the lever. The fitting of the links 32 upon opposite sides of the lever 15 will hold the same against side displacement from engagement with the block 28 and as the fitting of the block within the notch 26 will hold the lever from longitudinal thrust, it is obvious the shutter will be 20 firmly held in an open position. Due to the oblique angle the shutter is held in when in an open position, with respect to the surface of the body 11 of the vehicle, it is obvious that the air currents caught by the shutter 25 will be deflected through the opening of the frame 12 into the vehicle body for the purpose specified.

If it is not desired to have such air currents passing into the vehicle body, as during cold weather or when it is raining, for under such conditions rain would pass into the vehicle body, the operator may grip the inner end of the lever 21 and lift the same upwardly from engagement with the block 28 and then draw inwardly thereupon, which action will cause the links 32 to move in a clockwise direction as indicated by the dotted lines in Fig. 4. As the lever 21 moves inwardly, it will therefore swing the shutter 17 to a closed position. When the shutter finally engages the surface of the frame 12, the lever as well as the links will again assume a horizontal extension, thus causing the block 28 to be received in the notch 25 adjacent the end of the lever connected to the clip 23. This engagement therefore will hold the shutter in a closed position, since the notches are in direct alignment with the center of the pivotal point of securing of the lever, thereby preventing the shutter from being accidentally thrown to an open position, while as above explained, fitting of links upon opposite surfaces of the lever will hold the same from side displacement from the block 28. It should also be understood that due to the pivotal support of the block and also of the end of the lever connected to the shutter, the links and lever may be permitted proper movement to accommodate the arc of a circle in which the outer end of the shutter moves when moving either to an open or a closed position.

It will therefore be noted that a very simple and efficient means has been provided

for deflecting air currents into the body of a motor vehicle when it is desired to cool the interior thereof, although this means may be closed to prevent the beating of the weather into the interior of the vehicle body. Furthermore, it will also be noted that the latching means is positive in operation to retain the shutter in either an open or a closed position, this latching means being capable of very quick and easy movement for accomplishing the desired results of opening or closing and then retaining the shutter in the position it has just assumed.

The foregoing description and the drawings have reference to what may be considered the preferred, or approved form of my invention. It is to be understood that I may make such changes in construction and arrangement and combination of parts, materials, dimensions, et cetera, as may prove expedient and fall within the scope of the appended claims.

Having thus fully described my invention, what I claim as new and desire to secure by Letters Patent is:—

1. In a device of the class described, the combination with a frame, a bracket carried by said frame, a block pivotally mounted upon said bracket, a shutter pivotally mounted upon said frame, a staple carried by said shutter, a clip pivotally mounted upon said staple, a lever pivotally mounted upon said clip, said lever having notches therein, a pair of links pivotally mounted upon said block and also upon said lever, said links fitting upon opposite surfaces of said lever, said lever being adapted to be moved to move the shutter to an open or a closed position, at which time said block will fit within a desired notch while said links will hold the lever from side displacement from engagement with said block.

2. In a device of the class described, the combination with a frame, a bracket carried by said frame, a block pivotally mounted upon said bracket, a shutter pivotally mounted upon said frame, a staple carried by said shutter, a clip pivotally mounted upon said staple, a lever pivotally mounted upon said clip, said lever having notches therein, said lever being adapted to be moved to move the shutter to an open or closed position at which time said block will fit within a desired notch.

3. In a device of the class described, the combination with a frame, a bracket carried by said frame, a block pivotally mounted upon said bracket, a shutter pivotally mounted upon said frame, a staple carried by said shutter, a clip pivotally mounted upon said staple, a lever pivotally mounted upon said clip, and having notches therein, means pivotally connecting said lever to said block and engaging opposite sides of said lever, said lever being adapted to be

5 moved to move the shutter to an open or closed position at which time said block will fit within a desired notch, while said means will hold the lever from side displacement from engagement with said block.

4. In a device of the class described, the combination with a frame, a bracket carried by said frame, a block pivotally mounted upon said bracket, a shutter pivotally mounted upon said frame, a lever pivotally mounted upon said frame, a lever pivotally mounted upon said shutter, said lever having notches therein, a pair of links pivotally mounted upon said block and also upon said lever, said links fitting upon opposite surfaces of said lever, said lever being adapted to be moved to move the shutter to an open or closed position at which time said block will fit within a desired notch, while said links will hold the lever from side displacement from engagement with said block.

20 5. In a device of the class described, the

combination with a frame, a bracket carried by said frame, a retaining member movably mounted upon said bracket, a shutter pivotally mounted upon said frame, a lever pivotally mounted upon said shutter, said lever having notches therein, and a pair of links pivotally mounted upon said retaining member and also upon said lever, said lever being adapted to be moved to move the shutter to an open or closed position, at which time said retaining member will fit within a desired notch, while said links will hold the lever from side displacement from engagement with said retaining member.
